UNITED STATES PATENT OFFICE.

WALTER L. WILKS, OF BRIDGEPORT, CONNECTICUT, ASSIGNOR TO THE
HOLMES & EDWARDS SILVER COMPANY, OF SAME PLACE.

DESIGN FOR A SPOON.

SPECIFICATION forming part of Design No. 19,649, dated February 11, 1890.

Application filed January 18, 1890. Serial No. 337,386. Term of patent 14 years.

To all whom it may concern:

Be it known that I, WALTER L. WILKS, a citizen of the United States, and a resident of Bridgeport, in the county of Fairfield and State of Connecticut, have invented a novel 5 Design for Spoons, of which the following is a specification.

This invention relates to a design for the handles of spoons, forks, and other articles 10 of table-service; and it consists in the ornamentation of the surface of the shank and blade of the handle, as herein described, and shown in the accompanying illustration. The handle is substantially oar-shaped in out- 15 line, and the blade is provided with a raised bead or thread *a* on its edges, and parallel with this outer beading or thread there is a smaller thread *b*. The upper end of the handle has a shell-like ornament *c*, comprising 20 a number of lobes or scallops, the ends of which merge into a smooth and rounded projection *d*, forming the extreme edge of the handle. Below this ornamentation there is 25 a blank space tapering toward the bowl and having a number of beads *f* on each side of

its tapered end, the inner lines, defining the inner blank space, being curved outwardly at *e* below the beads. Lower down the handle are a number of beads *g*, and between these and the blank space is a flower-like or- 30 namentation *h*, and below the beads are the ribs *i*. The lower end of the shank is smooth and rounded and provided with a number of lobes *j*, extending to the bowl, the upper ends merging into the rounded portion of the 35 shank.

The leading features of my design consist in the bead-like ornamentations, the inter- 40 posed flower-like ornamentations, and the end ornamentations.

I claim—

A design for handles for table-ware, sub- 45 stantially as herein shown and described.

In testimony whereof I have signed my name to this specification in the presence of 45 two subscribing witnesses.

WALTER L. WILKS.
